FLY-ASH HANDLING APPARATUS

Lester Elliott, Springfield, Ill.

Application December 10, 1948, Serial No. 64,490

12 Claims. (Cl. 110—165)

1

This invention relates generally to fly-ash handling apparatus for commercial furnaces in which solid fuels are burned, and it is a general object hereof to provide improved apparatus adapted to facilitate the continuous removal of fly-ash deposits.

It is well known that solid fuel burning furnaces require some provision for enabling the removal of fly-ash which is deposited therein. The more advanced furnace installations are generally or more usually equipped with mechanical or hydraulic fly-ash removing apparatus which is expensive to install and operate. The heretofore prevailing mechanical apparatus, because of its initial cost and complicated nature is most often used only in the larger furnaces. The hydraulic apparatus is sometimes found objectionable due to the lack of proper space accommodations, because of the peculiarity of furnace construction required to accommodate it, and for other reasons.

Accordingly, the present invention has as an important object the provision of simple, inexpensive and easily installed fly-ash handling apparatus suitable for use in a variety of commercial furnaces, whereby the objectionable features of prior apparatus may be obviated.

It is also an important object hereof to provide improved apparatus which can be utilized in connection with existing furnace installations to improve operation thereof without requiring costly or extensive installation modifications.

Another object of the present invention is attained in a hopper assembly having structural and other useful features especially adapting the same for the rapid, effective and continuous withdrawal of fly-ash and like incombustibles from a furnace.

Still another object of the invention is to combine a hopper structure and means operating in cooperation with the hopper to direct and constantly feed fly-ash deposits into the hopper, such means being exemplified by an agitating and crushing member rotatively disposed within the inlet portion of the hopper and having a close working fit with the hopper walls, whereby loose fly-ash particles are relatively easily passed into the hopper and agglomerated or sintered ash formations are first crushed or broken up sufficiently to render them admissible to the hopper.

A further object of the invention is attained in the combination with the above mentioned hopper structure and assembly, of a fly-ash disposal blower system associated with the hopper

2

outlet and leading to a discharge in the region of the furnace fire box, whereby the fly-ash passing to the hopper is sucked into the blower system and returned to the fire box for recovery of residual heat values in the fly-ash and more complete combustion.

Other objects hereof will appear more particularly from the following description of a presently preferred structure and assembly, particular attention being directed to the drawing forming a part of this specification, and wherein:

Fig. 1 is a generally schematic view, in sectional elevation, of a furnace in which the improved hopper assembly has been incorporated in conjunction with a blower system;

Fig. 2 is an enlarged and fragmentary plan view, in section, of portions of the disclosure of Fig. 1 as seen at line 2—2 thereof;

Fig. 3 is a perspective view of the hopper assembly, with a portion of one wall broken away to disclose interior details;

Fig. 4 is a fragmentary sectional view, as seen at line 4—4 of Fig. 2, of the inlet zone of the hopper to show the relation of the agitator bar thereto;

Fig. 5 is a fragmentary end view of the hopper assembly showing a removable bearing block for the agitator member;

Fig. 6 is an exploded view in perspective of the agitator member, and portions of the drive shaft and shaft housing;

Fig. 7 is an elevational view of the power operated drive mechanism for the agitator member, as may be seen at line 7—7 of Fig. 2;

Fig. 8 is a perspective view of a modified form of agitator member having helical flights thereon, and

Fig. 9 is a vertical, fragmentary sectional view along line 9—9 of Fig. 2, showing an ash-ejector nozzle.

Referring to the drawing by suitable reference numerals it may be noted that the view of Fig. 1 discloses schematically and generally a commercial furnace structure 10 having a front wall 11, a bridge wall 12 spaced rearwardly of the front wall and a rear wall 13 beyond the bridge wall. Side walls 14 complete this portion of the furnace and thereby define a firebox region above the fuel supporting grate members 15 and in front of the bridge wall 12, and a combustion zone or region extending over and beyond the bridge wall. The furnace may be provided with banks of water tubes which extend between the front and rear walls, and for present purposes

only a portion 16 of the lowermost tube bank has been included.

In a furnace of this general character, the ignition of the fuel occurs in the firebox region above the grates 15, while the combustion thereof extends into the zone over the bridge wall 12 and above a fly-ash collecting pit defined by the furnace region between the bridge wall 12 and side and rear walls 14 and 13, respectively. The fly-ash pit is generally indicated at 17. It is, of course, understood that the fly-ash deposited in this pit 17 is for the most part, comprised of incompletely burned fuel particles which settle by gravity effects. As a consequence, such fly-ash may fuse and form larger agglomerate masses upon continued and prolonged exposure to the intense heat radiating thereto from above.

It is important, therefore, to remove the fly-ash as quickly as possible to prevent its undue exposure to the heat of combustion, and to reduce any later difficulties in effecting its removal. The present invention is principally directed to improved means for removing this fly-ash, and the following description will serve to point out the features and improvement therein.

In the example shown in Fig. 1, the furnace fly-ash pit 17 is formed with a thick bottom wall 18 of usual masonry construction, this wall having an upper funnel shaped surface which slopes or converges in each of the four principal planes to a bottom opening 19 of elongate or rectilinear form. The convergent faces of the wall 18 are lined with glazed or other form of fire brick 20 to provide protection for wall 18 against heat destruction and fly-ash erosion.

The improved fly-ash receiving hopper assembly 22, shown in more detail in Fig. 3, is disposed within the bottom opening 19 of the pit 17, and the space about the hopper is closed off by skewed bricks 23 cemented in place and partly supported on ledge elements 24 carried by the hopper. Thus, the fly-ash particles falling into the pit 17 are directed by the converging walls toward the bottom opening 19, and through the provision of agitating and crushing means associated with the hopper 22 such fly-ash is easily caused to pass into the hopper 22 at a rate which will eliminate the tendency of the fly-ash to fuse or bridge over the opening 19.

As may be seen in Figs. 1 and 2, the fly-ash passing into the hopper 22 is positively removed therefrom by a pneumatic disposal system. This system includes a motor driven blower 25, and an air conduit 26 connecting the blower outlet with a suitable conduit 27 located below the furnace and below the hopper 22. The conduit 27 emerges from below the furnace at the outer portion 28, and this portion 28 may extend to a discharge end (not shown) located in the front wall 11 of the furnace so as to deliver the fly-ash into the firebox for recovery of the heat values contained in the unburned portions thereof. Where the conduit 27 passes below hopper 22 (Figs. 1 and 2), there is provided an injector nozzle 29 and a suitable lateral inlet opening for fly-ash admission to the conduit 27 and entrainment thereof with the air flowing through the conduit past the nozzle 29. This nozzle 29 develops a negative pressure or suction effect in the hopper 22 and assists the movement of fly-ash through the hopper and into the conduit 27.

Turning now to Figs. 3, 4 and 5, the hopper 22 is seen to be formed of a pair of casting parts 31 of substantially the same form and arrangement so that the parts may be placed in matching

abutment when assembled. Since the castings are substantially identical, the same reference numerals will serve to indicate like parts of each. Thus, each casting 31 includes a flat side wall 32, 5 and opposite end wall portions 33 which are oppositely angularly directed from an elongate upper margin 34 to a lower margin 35. The upper margin 34 and the opposite, lower margin 35 are each free of any wall parts so as to provide 10 inlet and outlet openings for the hopper. The upper marginal portions of the castings 31 are each laterally extended, as at 36, to form spaced side wall elements defining spaced seat zones in conjunction with extended lip portions 37 of the 15 marginal end walls 33. In assembly, the castings 31 are disposed in facing relation with the marginal end walls 33 in abutment (Fig. 3), thereby placing the flat side walls 32 in closely spaced relation to form an elongate and rectilinear inlet opening 38 at the top of the hopper 22 and a reduced bottom outlet port between the lower margins 35. This bottom port is further defined by the securing of an adapter ring or short tube 39 welded or otherwise secured to the margins 35 and end walls 33. The two castings 31 are held in assembly by a plurality of screws 40 slidably disposed in suitable bosses 41 in one casting part and threadedly engaged in matching bosses 42 in the other casting part.

When assembled, the hopper 22 provides a convergent body passage 43 having the inlet opening 38 and the opposite outlet port in the adapter ring 39. This passage 43 is further divided into a plurality of convergent channels by the addition 30 of coaxing internal projections, deflecting flanges or vane elements 44, 45, 46, and 47. Each casting part 31 carries a set of these vane elements so that the vanes of one part abut those of the opposite part to bridge the side walls 32.

Fig. 3 illustrates the disposition of such vanes on one casting part, and it is to be noted that the several vanes coact to form convergent channels. Thus, vane 44 coacts with the adjacent end walls 33 to form a convergent channel 44C, vanes 44 40 and 45 form channel 45C, vanes 46 and 47 form channel 46C, and vane 47 and the adjacent end walls 33 form channel 47C. The area between vane elements 45 and 46 is closed at the top by the abutment thereof and, hence, does not constitute an effective channel. Since the adapter ring 39 is connected into the air conduit 27 at the zone of the injector nozzle 29, the suction effect thereof is communicated to the hopper passage 43, and the present disposition of vane elements has the effect of distributing this suction flow in a uniform manner throughout the hopper 45 50 passage with the result that fly-ash is more readily drawn through the hopper 22.

In conjunction with a hopper assembly of the above described character, there is provided an agitator member or rotating bar 50, shown in Figs. 2, 4 and 6. The member 50 is substantially square in section, and extends from a fixed type bearing block 51 to adjacent a removable bearing block 52 at its opposite end. The bearing 51 is mounted in one hopper seat (Fig. 3) and is provided with a suitable bearing aperture to receive the axially extended journal element 53 of the member 50. The opposite bearing block 52 is removably held in its hopper seat by a cap screw 54 (Fig. 5), and is provided with a bearing aperture to receive one end of a drive shaft 55. The shaft 55 projects through the bearing 52 and engages in a socket 56 in the end of member 50 where it is releasably pinned by element 70 75

57. Thus, the member 50 is operatively and removably mounted across the hopper inlet opening 38 and within the side walls 32 thereof. It is preferred that the member 50 have a close working fit within the hopper inlet 38 (Fig. 4) so that when it is disposed with its greatest width spanning such opening, fused or massed fly-ash particles may be crushed by it against the side walls 32. At other times, the loose fly-ash particles may freely pass into the hopper.

The drive shaft 55 for the member 50 extends through the adjacent furnace side wall 14 and is enclosed by a tubular housing 58, the latter housing also extends outwardly of the wall 14 and is seated in a close fitting wall sleeve element 59 to reduce the wall opening as far as possible. The outer end of the drive shaft projects beyond the housing 58, as at 60 (Figs. 2 and 7), and carries a ratchet gear 61 which is keyed or otherwise removably fixed thereto. A pawl arm 62 is freely pivoted on the shaft end portion 60 adjacent the gear 61, and this arm 62 carries a pawl or finger element 63 which is operatively arranged to engage the ratchet teeth when the arm 62 is pivoted in a counter-clockwise direction, as viewed in Fig. 7. The clockwise direction of movement of the arm 62 merely causes the element 63 to ride over the ratchet teeth without driving engagement. Actuation of the arm 62 is obtained through an elongate driving tape 64 arranged for reciprocating movement within a tubular or other suitable housing 65. This tape 64 and its housing 65 extend to a drive means (not shown), but which, as is indicated on the drawing, might be the drive arm of a stoker mechanism used to supply fuel into the furnace. However, any suitable source of power could be employed for this purpose as, for example, a motor driven crank mechanism to which the tape 64 would be connected to produce the proper rate of reciprocating movement at pawl arm 62. In this way, the agitating and crushing member 50 is rotated in a step-by-step manner, and is caused to effect the desired agitation and crushing action on the fly-ash whereby the same may be easily passed into the hopper 22.

In Fig. 8, there is shown a modified agitator member 68 of the screw type. This member has a cylindrical body about which is secured a spirally formed element 69. The element may be of one piece or several pieces arranged to provide a continuous screw flight. When member 68 is employed in place of member 50, the flight 69 is made to have a close working clearance within the inlet 38 of the hopper 22 and between the spaced side walls 32. The manner of operatively mounting member 68 is identical with that described for member 50.

The foregoing description is specifically directed to a presently preferred form of the invention, but it should be understood that certain variations of construction of the several parts and changes in the manner of assembly thereof can be effected without departing from the intended scope of the appended claims.

I claim:

1. In an ash receiving assembly for feeding ash to a pneumatic conveying system in a commercial furnace, the combination of a hopper body having an inlet and an outlet provided with a pneumatic connection, and enclosing walls defining a plurality of passages converging toward said outlet from said inlet, bearings positioned at said body inlet in spaced relation, an agitator member extending across said inlet and operatively sup-

ported by said spaced bearings, said member having a close fit in the body inlet sufficient to permit loose ash particles to pass into the body and to permit agglomerate ash masses to pass when crushed between said member and the adjacent body walls, and an operating shaft rotatively supported by one of said spaced bearings and connected to said agitator member for operatively rotating the same.

10 2. An ash receiving hopper assembly comprising closely spaced side walls and opposite end walls cooperating with said side walls to form a hopper body characterized by an inlet of elongate rectilinear aspect, a restricted outlet, and a body passage convergently directed toward said outlet, and an ash agitator and clinker crushing member operatively disposed across said body inlet between and just below the upper margins of said side walls, said member being adapted for rotation about its longitudinal axis and having a close working clearance between said side walls, whereby loose ash particles are free to pass into the body passage and agglomerate ash formations are substantially crushed prior to entrance into said body passage.

3. An ash receiving hopper assembly as defined by claim 2 and in which said rotating member consists of an elongate bar substantially square in cross section and having a diagonal dimension less than the spacing of the side walls as determined by the close working clearance.

4. In a fly-ash collecting hopper assembly for use in and with a pneumatic ash transporting system in a commercial furnace, a hopper body formed with closely spaced and parallel side walls and opposite end walls extending between the side walls to define a body passage open at its upper and lower margins said body having bearing seats formed between said side walls, with one seat at the upper end portion of each end wall, a bearing block carried in each seat, an ash agitating and crushing member operatively mounted in said bearing blocks and having a close working clearance between said body side walls within the margins thereof, and drive means operatively connected with said member.

5. A hopper for use in connection with the collection and disposal of furnace fly-ash material, the hopper including matching metal parts, each having a side wall and opposite marginal end wall portions which are oppositely convergently directed from an elongate upper wall margin to an opposite and reduced lower wall margin, means securing said matching parts in assembly with said marginal end wall portions in registering abutment to constitute convergent end walls of the hopper for a hopper passage having an elongate top opening defined by said upper wall margins and an opposite, reduced bottom opening between the side walls, an agitator operatively disposed in, and substantially closing the top opening, and a plurality of vane elements carried by each matching part and positioned for abutting registration in bridging relation between said side walls.

6. A fly-ash disposal hopper for use in a furnace installation, the hopper including a pair of matching metal parts, each part having an outer side wall and a pair of opposite marginal end wall portions extending at one side of the outer side wall and convergently directed from an elongate and free margin thereof, means securing said matching parts in assembly with the marginal end wall portions in abutment to form enclosing end walls of the hopper and to maintain said

outer side walls in spaced relation to constitute a hopper passage having an elongate horizontal top opening, an agitating device extending substantially over the length of said opening, the said marginal wall portions of the matching parts abutting to form convergent end walls and a restricted bottom opening, and a plurality of vane elements carried by each matching part in position to extend into abutment and bridge the hopper passage between said side walls, the vane elements on each matching part being located between said marginal end wall portions, and further being alternately angularly directed so that the hopper passage is effectively sub-divided thereby into a plurality of elongate channels extending between said opposite openings.

7. A fly-ash hopper as defined in claim 6, and further characterized in that said side walls of said matching metal parts are maintained, when in assembly, in substantially parallel relation, and each of said elongate channels in the hopper passage is convergently formed and directed toward said bottom opening of the hopper passage.

8. In an ash-handling installation for use in a furnace having a fly-ash collecting pit, an air blower and connecting conduit leading from said blower beneath the fly-ash collecting pit, said conduit having a suction port opening toward the collecting pit, a device between said suction port and the collecting pit for directing fly-ash deposited in the pit into said suction port, said device comprising a hopper body formed with an elongate ash-receiving inlet in the pit and an outlet opening to said suction port, and a power driven ash-displacement member operatively mounted within said hopper inlet for agitating fly-ash deposits to facilitate passage thereof into said hopper body under the influence of gravity, suction and displacement effect of said power driven member.

9. An ash handling installation as defined in claim 8, further characterized in that said hopper body is downwardly convergent and is provided with internal vane elements extending between said body inlet and outlet, said vanes forming a plurality of separate passages downwardly convergent and so acting to equalize the suction effect produced at said suction port over substantially the full area of the body inlet.

10. A device for removing and reducing the contents of a furnace ash pit, including a hopper having an elongate rectangular inlet below the pit, and an outlet together with a suction connection in its lower portion, a crushing member positioned within and substantially fully occupying said hopper inlet and operably disposed to pass ash into said hopper and to prevent ash accumulations bridging the hopper inlet, a power driven element external to the pit and connected to said crushing member for operating the same, and a blower system having a conduit extending past the suction connection at said hopper outlet,

said system including a nozzle positioned in said conduit below said hopper outlet suction connection.

11. An ash crushing and feeding device for use with a fluid ash-transport system in a furnace provided with a fly-ash collecting pit having a convergent bottom, the device comprising a hopper body formed by side and end walls and defining an elongate, slotted inlet opening adapted for registration with the bottom outlet of the fly-ash collecting pit, the body side and end walls of the hopper also forming an outlet port and a fluid connection, a fly-ash agitating and crushing member operatively positioned within and extending across said body inlet opening over the length thereof, and a power driven operating element connected to said member and projecting externally of the furnace.

12. Fly-ash handling apparatus for use with pneumatic conveying apparatus in commercial furnaces, comprising a fly-ash receiving hopper formed by closely spaced and substantially parallel side walls and opposite end walls convergently directed, a plurality of internal projections carried by the side walls, and defining therewith hopper passages convergently extending from an elongate, rectilinear inlet mouth to an outlet port, a connection at the outlet port, for attachment to a pneumatic conveyor conduit, bearing elements located at opposite ends of the hopper inlet mouth between said side walls, and an elongate fly-ash agitating and crushing member rotatively supported at its opposite ends in said bearing elements, said member extending substantially from end to end of the inlet mouth and having a close working clearance with said side walls.
